Primary Examiner—Louis S. Zarfas**Assistant Examiner**—I. Simmons**Attorney, Agent, or Firm**—Allen, Dyer, Doppelt, Franjola & Milbrath, P.A.**[57]****CLAIM**

The ornamental design for a disposable surgical stab wound closure instrument, as shown and described.

DESCRIPTION

FIG. 1 is a top, left perspective side view of the disposable surgical stab wound instrument showing my new design in the stowed position;

FIG. 2 is a left perspective side view thereof, the right perspective side view being a mirror image;

FIG. 3 is a left perspective side view of a disposable surgical stab wound closure instrument showing my new design in the deployed position;

FIG. 4 is a top plan view of a disposable surgical stab wound closure instrument in the stowed position;

FIG. 5 is a bottom plan view thereof;

FIG. 6 is a front perspective view thereof;

FIG. 7 is a rear perspective view thereof;

FIG. 8 is a front perspective view of a disposable surgical stab wound closure instrument in the deployed position;

FIG. 9 is a top plan view thereof; and,

FIG. 10 is a bottom plan view thereof.
